UNITED STATES PATENT OFFICE.

ROBERT F. DARBY, OF YONKERS, NEW YORK.

DUST-GUARD.

1,356,046.

Specification of Letters Patent. Patented Oct. 19, 1920.

Application filed July 18, 1919. Serial No. 311,695.

To all whom it may concern:

Be it known that I, ROBERT F. DARBY, a citizen of the United States, and a resident of Yonkers, in the county of Westchester 5 and State of New York, have invented certain new and useful Improvements in Dust-Guards, of which the following is a specification.

This invention has for its main object 10 to improve the construction of dust-guards for car axle journal boxes and to provide a device of unusual simplicity, lightness and strength, readily engageable in car axle boxes of standard construction whereby dust, grit, 15 etc., are excluded, and waste of lubricant prevented.

Another object is to provide a sectional dust-guard yieldingly engageable with the axle by a novel device which constantly 20 maintains the sections in intimate and proper relation.

A further object is to construct one form 25 of the dust-guards in sections made from laminated plates composed of layers of veneer, the grain of the wood being disposed in alternate transverse relation so as to prevent warping or distortion, and the several layers firmly bonded by a cement impervious to moisture and wholly unaffected by lubricating oils, thereby avoiding the use of 30 rivets, screws and other analogous fastenings, while another form is comprised of a single sectional plate and bearing ring united thereto.

35 These objects are attained by the novel construction and combination of parts hereinafter described and shown in the accompanying drawings, forming a material part of this disclosure, and in which:—

40 Figure 1 is a perspective view showing a dust-guard made in accordance with the invention.

Fig. 2 is a front elevational view of the same, parts being broken away in order to 45 show the built-up construction.

Fig. 3 is a vertical sectional view taken on line 3—3 of Fig. 2.

Fig. 4 is an enlarged fragmentary transverse sectional view taken on line 4—4 of 50 Fig. 1.

Fig. 5 is a front elevational view showing a modified form of dust guard construction.

Fig. 6 is a vertical sectional view taken on line 6—6 of Fig. 5, and

55 Fig. 7 is a top plan view of the same.

Referring to the drawings in detail, the numeral 10 designates a conventional type of car axle-box, the same being provided at its inner or rear end with a chambered recess 11 through which extends the stepped 60 portion 12 of the axle 13, the same also passing through the dust-guard normally contained within the chamber.

The dust-guard as shown in Figs. 1 to 4, is formed in two plate sections, the upper 65 section 15 being rectangular and the lower, corresponding section 16, semi-circular or otherwise to conform to the axle-box.

United with the upper plate section 15, on one side, is the segment 17 of a ring, 70 its end 17' extending beyond the plane of its diametral center line, partially overlying the lower plate section 16 and abutting against the corresponding, but foreshortened, ends of the lower ring segment 18, 75 united to the side of the lower section 16.

The sections 15 and 16 are composed of 80 plates or layers of veneer, *a*, *b* and *c*, the outer layers being so arranged as to present the grain of the wood transversely to the center layer *b*, while the ring is similarly composed of a central, washer-like plate *e*, faced by plates *d* and *f*, the center plate being relatively thicker in order to properly fill the space in the chamber 11. 85

The opening 19, through which the axle 12 passes, is concentric with the ring elements and the joint between juxtaposed edges of the plate sections 15 and 16 is in the plane of the center of the opening 19, 90 the extensions 17' acting to maintain the sections in lateral register in one direction.

These sections are further held in the same level plane, and also drawn resiliently together, by a spring wire having hook-like, 95 inturned terminals 20 bent to extend radially into the lower ring segment 18, on opposite sides, below the center and so close to the plate sections 15 and 16 as to contact with them.

These terminals 20 are formed with arms 21 extending in parallel along the side edges of the section 15, the arms merging by bent corners 22 into a spring cross-bar 23 bent slightly downward into a straight central portion 24, engageable in a groove 25 formed tangentially in the periphery of the segment 17, closely adjacent to the plate 15, and parallel with its upper edge. 105

Thus the wire 21 performs a double func- 110

tion; that of guiding the sections laterally, and drawing them together by reason of the integrally formed spring-bar 23.

It is to be noted that no rivets, screws 5 or other fastening means are employed, the only metallic part being the wire, bent to form the elements 20 to 24 inclusive.

Extreme lightness is attained by the use of relatively thin plate sections and the 10 reinforcing space ring, while adequate strength and freedom from warping is secured by the transverse disposition of the several layers, which are bonded together by a cement having the peculiar property 15 of being unaffected by water or oils, such as are used for lubricating purposes, even if subjected to the same for long periods.

In the modification shown in Figs. 5 to 7, a relatively thin plate comprised of sections 30 and 31, respectively upper and 20 lower, is used, each having in their adjacent edges equal semi-circular openings 32 and 33, of a size to clear the axle element 12.

Secured upon one side of this plate is 25 a ring composed of upper and lower sections 34 and 35, the upper section 34 having its ends 34' extended past the meeting line of the plate sections 30 and 31, the opening in the ring being of lesser diameter than that in the plate and suited to the axle element 12.

The ring sections 34 and 35 are firmly secured to the plate sections 30 and 31 by any adequate fastening means as exemplified by the screws 36 or analogous devices.

A spring wire is bent to form a pair of oppositely disposed hooks 37 engageable in appropriate openings formed in the periphery of the lower ring section 35, near its 40 ends the wire continuing in parallel elements 38, closely adjacent to the edges of the upper plate section 30, to a height above the ring, and then formed into spring coils 39 connected by a bowed portion 40, the 45 central, straight part 41 of which is in contact with the surface of the ring section 34 at its highest point, immediately over the center.

In order to maintain the spring wire in 50 engagement, in addition to the integral hooks 37, a pin 42 or the like may be inserted in the ring in contact with the part 41, or the device previously described employed.

55 In this modification it is possible to use a thin metal plate without damage to the axle, the entire weight of the guard being borne by the relatively wide wooden ring.

The foregoing disclosure is to be regarded as descriptive, rather than restrictive or 60 limitative of the invention, which in practice may be modified in minor details within the spirit and scope of the appended claims.

Having thus particularly described the 65 nature, construction and use of the inven-

tion, what is claimed as new and sought to be secured by Letters Patent, is:—

1. A dust guard comprising a wooden plate, a spacer secured to one side of and surrounding an opening through said plate, 70 said plate and spacer being in two horizontal sections, a connecting element formed of a single wire strand resiliently constraining the sections together, and means in each section of said spacer coöperating to hold 75 said connecting element in operative engagement.

2. A dust guard comprising a transversely bisected plate containing an opening, a split spacer ring extending therefrom having an 80 opening of lesser diameter concentric with the opening in said plate, the joints of said ring being offset to the joints of said plate, constituting means for holding said plate sections against lateral movement, and a 85 single unitary element resiliently engaging the sections of said plate in operative relation.

3. A dust-guard comprised of a sectional plate composed of a plurality of wooden 90 layers disposed alternately in transverse order, bonded by an impervious cement, and a unitary element resiliently maintaining the sections of said plate in juxtaposition, said element contacting with one of the 95 plate sections at one point and with the other section at two points equi-distant from the first named point.

4. A dust-guard comprising a laminated, 100 sectional plate, a ring segment affixed to one side of said plate on each section, a bent spring wire engaged at its ends in one of said segments, and a loop formed in said wire, said loop being received in a tangential groove formed in the other of said segments.

5. A dust-guard comprising a laminated wooden plate formed in two sections and having an axle opening extending equally 110 into each section, a laminated wooden ring segment fixed upon each plate section enclosing the mentioned opening, the ends of one of said segments overlapping the adjacent section, a spring wire having hooked ends engaged in one of said segments, said 115 wire passing closely to said plate over the other segment, and a part formed with said wire engaging in a tangential groove in the other of said segments.

6. A dust-guard comprising a horizontally sectioned plate containing a circular opening, a spacer ring secured to said plate, 120 said ring having a smaller opening concentric with the opening in said plate adapted to receive an axle, said plate being divided 125 transversely in a plane co-incident with the axis of its opening and said ring being divided in a plane parallel and below the axis, and a single retaining means for resiliently holding the sections in engagement. 130

7. A dust-guard comprising a relatively thin plate containing an opening, a ring secured to one side of said plate, said ring having a smaller opening concentric with the opening in said plate and receptive of an axle, said plate and ring being each in separable sections, a wire extending adjacent to said plate resting on one of the sections of said ring, means for maintaining said wire in position, spring coils formed in said wire, and hooks at the ends of said wire engaged in the other section of said ring.

8. A dust guard comprising a laminated plate divided transversely into upper and lower symmetrical sides, the lower section being an arc, and containing equally between them a circular opening, a laminated split ring secured laterally to said plate sections in such manner as to break joints therewith, said ring being concentric with the opening, and of lesser interior diameter, and a symmetrical resilient clamp element engaging said ring at three points adapted to hold the ring and plate in operative position.

9. A dust guard comprising a laminated plate divided transversely into upper and lower sections having between them a circular opening, a split spacer ring having its sections attached respectively to the sections of said plate and its joints in staggered relation to the joints of the plate, and a single unitary symmetrical spring element engag-

ing at its center with the top of one of the sections of said ring and at its ends with the sides of the other section thereof.

10. A dust guard comprising a laminated plate having an approximately rectangular upper section and an arcuate lower section, the sections each containing openings which together form a circle, semi-annular bands secured concentric to said opening, the ends of said bands meeting in a different plane from the joint of said plate sections, and a single spring wire bent to engage over one of said bands and enter oppositely formed openings in the other of said bands whereby their ends are held in contact.

11. A dust guard comprising a laminated plate having an approximately rectangular upper section and an arcuate lower section, the sections each containing openings which together form a circle, semi-annular bands secured concentric to said opening, said bands being of lesser diameter than the opening, the ends of said bands meeting in a different plane from the joint of said plate sections, and a single spring wire bent to engage said bands whereby their ends are held in contact, said wire also maintaining the elements of said plate from lateral motion.

In testimony whereof I have signed my name to this specification.

ROBERT F. DARBY.
